FISH LURE PROTECTOR

Clarence E. Smith, Rte. 2, Mabank, Tex. 75147

Filed Apr. 14, 1967, Ser. No. 6,690

Term of patent 14 years

(Cl. D22—31)

FIGURE 1 is a perspective view of a fish lure protector, embodying my new design;

FIGURE 2 is a modified embodiment of the fish lure protector illustrated in FIGURE 1; and

FIGURE 3 is a further modified embodiment of the fish lure protector shown in FIGURE 1.

The rigid rod elements disclosed in FIGURES 1 and 3 are broken away to indicate indeterminate length.

I claim:

The ornamental design for a fish lure protector, as shown and described.
